L. F. PARKHURST.
ELECTRIC SAD IRON AND TERMINAL BOX.
APPLICATION FILED FEB. 15, 1911. RENEWED APR. 1, 1912.

Patented May 28, 1912.

UNITED STATES PATENT OFFICE.

LEON F. PARKHURST, OF BINGHAMTON, NEW YORK, ASSIGNOR TO DIAMOND ELECTRIC COMPANY, OF BINGHAMTON, NEW YORK, A CORPORATION OF NEW YORK.

ELECTRIC SAD-IRON AND TERMINAL BOX.

1,027,666.

Specification of Letters Patent.

Patented May 28, 1912.

Application filed February 15, 1911, Serial No. 808,769. Renewed April 1, 1912. Serial No. 687,775.

To all whom it may concern:

Be it known that I, LEON F. PARKHURST, a citizen of the United States, residing at Binghamton, county of Broome, State of New York, have invented certain new and useful Improvements in Electric Sad-Irons and Terminal Boxes, of which the following is a full, clear, and exact description.

My invention relates to electrically heated sad irons and is particularly concerned with improved means for connecting the leads of the circuit wires from the source of energy with the terminals of the heating units in the iron, whereby connection will be effected at a point removed from the heat of the body of the iron, thus producing a more effective connection, while at the same time the terminals of the heat units will be conveniently arranged for ready connection of the leads without disturbing the assembly of the iron.

A further object is to provide an improved holder for the leads at the point of their attachment to the iron which will relieve the connections with the unit terminals of all pulling strain, and will, at the same time, so position the end of the cable carrying the leads that it will not interfere with the operation of the iron and will be preserved against breaking strain.

With these objects in view, the invention consists in the construction and arrangement of parts, a preferred embodiment of which is illustrated in the accompanying drawings, in which—

Figure 1 is a fragmentary view of the rear end of an electric sad iron showing my invention in conjunction therewith; Fig. 2 is a sectional view on the line 2—2, Fig. 1, of a terminal box embodying certain features of my invention; Fig. 3 is a sectional view on the line 3—3, Fig. 2; Fig. 4 is a sectional view on the line 4—4, Fig. 2; Fig. 5 is a detail view of a part of the cable holder attaching the cable to the iron, and Fig. 6 is a detail view of the connectors employed in the terminal box.

In the embodiment of my invention herein selected for illustration, 1 indicates the base of the iron, 2 the cover therefor, 3 the handle bail and 4 the handle.

The base of the iron is provided with an integral raised portion 5 within chambers in which the heat units 6—6 are suitably mounted and arranged, and the cover 2 forms a heat insulating air space 7 around

the portion 5 carrying the heat units. The terminals 8—8 of the heating units are led out through an insulating sleeve 9 in the cover plate and are secured to binding screws 10—10 in a terminal box comprising a base 11 suitably secured to the handle bail 3 and having therein a porcelain block 12 between which and the base of the box is suitably interposed a layer 13 of insulating material, such as asbestos lumber. Heat insulating washers 14 may be interposed between the handle bail and the base of the box if desired. As indicated in Figs. 2 and 4, the porcelain block is notched, or slotted, at 15 to receive the terminals 8, which notch is inclined from a point near the base of the block to the level of the raised seats in which the connecting members, or plates, 16—16 are mounted, which plates are held in position by screws 17—17 and receive the binding screws 10—10 respectively at one end. At the opposite end of these plates are binding screws 18—18 to which the leads 19—19 of the cable 20 are attached. The porcelain block is also provided with a second notch 21 similar to and preferably located diametrically opposite the notch 15 to receive the cable 20. The box is provided with a suitable cover 22, preferably lined with insulating material, such as a layer 23 of paper, and both the cover and the lining are slotted at 24—25 to pass the heating terminals and the cable. To attach the cover to the box securely, and without distorting the same, the porcelain block 12 is provided with a tubular post 26 to receive a screw 27 which is threaded into the handle bail 3 and secures the cover in place.

By the above described construction, it will be seen that the terminals of the heating units are led out of the body of the iron and are secured at a convenient point for connection with the leads of the energy circuit. Furthermore these connections are considerably removed from the heating effects of the body of the iron and are further shielded by the terminal box.

In order to preserve the terminal box and the connection therewith of the circuit leads from undue strain on the supply cable, the latter is secured to the iron by means of a suitable attaching bracket comprising a semi-cylindrical member 28 having integral therewith an attaching arm 29 which may be conveniently secured to the handle bail by means of the bolt 4' which secures the

handle thereto, said arm being strengthened by reinforcing flanges 30-30. A second semi-cylindrical member 31 is attached to the first by means of ears 32 formed to register with ears 33 on the member 28. The outer ends of the members 28 and 31 are enlarged somewhat as at 34, and such enlargement may have stamped therein a thread to receive a spirally arranged protecting wire or armor 35 on the cable 20, which preserves the latter against bending strains at the point of attachment. The two members 28 and 31, when clamped upon the cable, grip the same firmly and cause the threaded portion 34, at the same time, to take a firm hold upon the wire 35, hence this attaching member takes all of the pulling strain upon the cable and relieves the terminal box and the connection from said strain.

20 While I have herein described a particular embodiment of my invention, it is to be understood that the same may be altered in details and in the relative arrangement of parts within the scope of the appended claims.

What I claim is:

1. In an electric sad iron, the combination with an iron body having heating units therein, of a terminal connector located outside of said body having the terminals of said units secured thereto, of a supply cable having circuit terminals leading into said connector and means for securing said cable to said iron independently of said terminal connections to preserve said terminal connections from pulling strains on said cable.

2. In an electric sad iron, the combination with an iron body having heating units therein, a handle for said iron, a terminal connector mounted on said handle outside of said iron body and removed from the heating effects thereof and having the unit terminals connected therewith, of a supply cable having its terminals connected with said connector and means for securing said cable to said handle independently of said connections with said connector.

3. In an electric sad iron, the combination with an iron body having heating units therein, a handle for said body, a supply cable, a connector mounted on said handle to receive the terminals of said units and said cable, and a bracket for securing said cable to said handle independently of the connections with said connector.

4. In an electric sad iron, the combination with an iron body having heating units therein, a supply cable, a connector mounted on said iron outside of said body and adapted to receive the terminals of said units and said cable and a clamp located beyond said connector for securing said cable to said iron independently of said connector.

5. In an electric sad iron, the combination with an iron body having heating units therein, a supply cable, a connector for the terminals of said units and said cable located outside of said iron and a clamping bracket for attaching said cable to said iron independently of the connection with said connector.

6. In an electric sad iron, the combination with an iron body having heating units therein and having a handle bail attached thereto, a handle attached to said bail, a supply cable, a connector mounted on said handle bail and adapted to receive the terminals of said units and said cable, and an attaching bracket secured to said handle bail by the means for attaching said handle thereto, said cable attachment being independent of the connection of its terminals with said connector.

7. In an electric sad iron, the combination with an iron body having heating units therein and having a handle, a supply cable, a terminal box mounted on said handle adapted to receive the terminals of said units and said cable, a bracket attached to said handle beyond said terminal box to secure said cable to said iron whereby the connection of said cable with said terminal box will be relieved of pulling strains upon said cable.

8. In an electric sad iron, the combination with an iron body having heating units therein, a supply cable therefor, a terminal connector on said iron adapted to receive the terminals of said units and said cable, an attaching clamp for said cable comprising a semi-cylindrical portion having an attaching bracket adapted to be secured to the handle of said iron, and a second semi-cylindrical portion co-operating with the first to clamp and hold said cable.

9. In an electric sad iron, the combination with an iron body having heating units therein, a supply cable, a terminal connector for the terminals of said units and said cable, said cable having a spirally arranged armor, an attaching member for said cable comprising a semi-cylindrical portion having a bracket adapted to be attached to the handle of the iron and having an enlargement at its outer end, a second semi-cylindrical portion co-operating with the first and having an enlargement at its outer end coinciding with that of the first, said enlargements being internally threaded to receive said spiral armor, and means to clamp said portions together upon said cable and in engagement with said armor.
